The ornamental design for a combined portable accessory carrier and headset, as shown and described.

DESCRIPTION

FIG. 1 is a front, right end and top perspective view of an combined portable accessory carrier and headset showing my new design;

FIG. 2 is a front elevational view thereof;

FIG. 3 is a rear elevational view thereof;

FIG. 4 is a right end elevational view thereof;

FIG. 5 is a left end elevational view thereof;

FIG. 6 is a top plan view thereof; and,

FIG. 7 is a bottom plan view thereof.

The broken lines shown in the bottom portions of FIGS. 1 and 3 represent a folded blanket or the like and form no part of the claimed design, and the dashed line showings on portions of the design as shown in FIGS. 1, 4, and 5 represent conventional stitching.
